UNITED STATES PATENT OFFICE.

GEORGE HENRY HARLAND, OF GODERICH, CANADA.

COUNTER-SUPPORT.

SPECIFICATION forming part of Letters Patent No. 729,761, dated June 2, 1903.

Application filed August 12, 1902. Serial No. 119,436. (No model.)

To all whom it may concern:

Be it known that I, GEORGE HENRY HARLAND, a citizen of Canada, residing at Goderich, in the county of Huron, Dominion of Canada, have invented new and useful Improvements in Counter-Supports, of which the following is a specification.

My invention relates to improvements in boot and shoe counter supports—*i. e.*, devices having tangs adapted to be secured in the heels of boots and shoes and body portions shaped to rest at the sides of the counters thereof—with a view of preventing the counters being forced out of shape incident to wear of the boots and shoes.

The invention consists in a certain peculiar counter-support the novelty, utility, and practical advantages of which will be fully understood from the following description and claim when taken in conjunction with the accompanying drawings, in which—

Figure 1 is a side elevation of a portion of a shoe equipped with one of my improved counter-supports. Fig. 2 is a transverse section taken on the broken line 2 2 of Fig. 1, with one of the tangs of the support partly in elevation; and Fig. 3 is a perspective view of the counter-support removed.

Referring by letter to said drawings, A is the counter, and B the heel, of a shoe, and C is my improved counter-support. This support is formed of one piece of iron or other suitable metal, and consists, essentially, of a flat body *a*, the lower end of which is increased in thickness to form an exterior shoulder *b*, and parallel tangs *c*, which extend downwardly and inwardly from the lower end of the body and in conjunction with said body describe an approximate obtuse angle. The tangs *c* describe a left-hand curve in the direction of their length, as best

shown in Fig. 2, and consequently they are enabled when driven into the heel *B* by hammer-blows applied to the shoulder *b* to draw the body *a* up firmly against the counter *A*, so as to enable said body *a* to properly support the counter and hold the same against outward movement. The left-hand curvature of the tangs *c* in the direction of their length is also advantageous, 50 since when they are driven into a heel they are not liable to work loose, and hence do not have to be clenched, as do the straight tangs of the counter-supports extant.

My improved supports are adapted to be applied to either or both sides of the counter of a boot or shoe, and they are obviously calculated by holding the counter against outward movement to retain the same in its original shape, and thereby prolong the usefulness of the boot or shoe, and this without rendering the boot or shoe cumbersome or unsightly.

Having described my invention, what I claim, and desire to secure by Letters Patent, 65 is—

As an improved article of manufacture, the herein-described counter-support, formed of one piece of metal, and consisting essentially of the flat body *a* having the exterior shoulder *b* at its lower end, and the parallel tangs *c*, which in conjunction with the body describe an approximate obtuse angle, and which describe a left-hand curve in the direction of and throughout their length. 75

In testimony whereof I have hereunto set my hand in presence of two subscribing witnesses.

GEORGE HENRY HARLAND.
